UNITED STATES PATENT OFFICE.

BENJAMIN SKIDMORE, JR., OF CHICAGO, ILLINOIS.

SUCTION-CREATING APPARATUS.

1,382,444.

Specification of Letters Patent. Patented June 21, 1921.

Application filed March 27, 1919. Serial No. 285,488.

To all whom it may concern:

Be it known that I, BENJAMIN SKIDMORE, Jr., a citizen of the United States, residing at Chicago, in the county of Cook and State 5 of Illinois, have invented certain new and useful Improvements in Suction-Creating Apparatus, of which the following is a specification.

This invention relates to improvements in 10 suction creating apparatus and one of the objects of the invention is to provide an improved apparatus of this character for creating suction in a passage or chamber and embodying an impeller which in turn 15 embodies spaced concentrically arranged and simultaneously rotating impeller blades or wings having a space therebetween and across which space the liquid is delivered from one set of blades to the other, the distance 20 of the liquid from the outermost blades or wings operating to create a suction across the said space and which suction is manifested in a chamber or conduit having communication with the space.

25 A further object is to provide an improved apparatus of this character embodying volute shaped passages into which the liquid displaced by the impeller is discharged and with which passages the conduit or chamber 30 has communication whereby the kinetic energy of the liquid in the volute passages after the impeller has ceased to discharge the liquid thereinto will cause an additional and further suction in the fluid conduit or 35 chamber.

To the attainment of these ends and the accomplishment of other new and useful objects as will appear the invention consists 40 in the features of novelty in substantially the construction, combination and arrangement of the several parts hereinafter more fully described and claimed and shown in the accompanying drawing illustrating this invention and in which;

45 Figure 1 is a vertical longitudinal sectional view of an improved apparatus of this character constructed in accordance with the principles of this invention and as taken on line 2—2, Fig. 2.

50 Fig. 2 is an irregular vertical sectional view as taken on line 2—2, Fig. 1.

Fig. 3 is a view taken on line 3—3, Fig. 2.

Referring more particularly to the drawing the numeral 10 designates a tank within 55 which the apparatus may be located and this tank is provided with a fluid outlet 11.

The tank may be of any desired size and configuration and supported in any suitable manner such as by means of legs 12.

Arranged within the tank is a casing 60 designated generally by the reference numeral 13 which is provided with an inlet opening 14 adjacent its center and rotatably mounted within the casing is an impeller 65 designated generally by the reference numeral 15. This impeller is mounted upon a shaft 16 journaled in suitable bearings 17—18, preferably supported by the walls of the tank and the shaft is adapted to be rotated by means of a suitable motor 19. 70 The impeller preferably embodies a plurality of impeller blades or wings 20 radially disposed and which project beyond the body of the impeller. If desired another set of impeller blades 21 may be provided on the 75 impeller intermediate the blades 20. All of these blades are preferably of a curved shape, the inner ends of which terminate short of the axis of the impeller and the outer ends terminate considerably short of 80 the periphery of the impeller. The impeller is also provided with a series of blades 22 arranged adjacent the periphery thereof to form pockets thereupon. These blades 22 may be disposed at any angle with respect 85 to the axis of rotation and are of a length to extend from the periphery of the impeller 15 and terminate considerably short of the outer ends of the blades 20—21 so as to form a space 23 intermediate the concentric series 90 of impeller blades. The two series of blades are connected with the impeller for simultaneous rotation and the blades are so arranged that the liquid from the tank 10 will enter the casing 13 through the opening 14 95 to be delivered to the center of the impeller where it will be caught by the blades 20—21 as the impeller rotates and these blades will deliver or discharge the liquid outwardly therefrom by centrifugal action to the 100 pockets formed by the blades 22. The liquid is discharged across the space 23 between the two series of impeller blades, and means are provided whereby a suction will be created in a conduit or passage 24. This may be accomplished in any suitable manner but preferably by means of passages 25 which have communication with the conduit 24. These 105 passages 25 are so shaped that the ends 26 thereof will extend into the space 23 between the series of impeller blades, one side 27 of these passages 26 is open as shown more

105

110

clearly in Fig. 2, in the direction of the outer series of impeller blades 22 while the wall of the passages 26 form abutments or baffles which are arranged adjacent the path 5 of the movement of the outer ends of the blades 20, 21. As the liquid is displaced by the blades 20—21, it will be delivered, as before noted, into the pockets formed by the blades 22, across the space 23 intermediate 10 the ends of the passages 26, and as the impeller rotates, the wall formed by the passage 26 will interrupt the delivery of the liquid by the blades 20—21 to the pockets formed by the blades 22. The liquid which 15 has been delivered into the peripheral pockets will be thrown out of these pockets by centrifugal force at the time when the respective pockets or blades 22 are passing the open portion 27 of the passages 26 and this 20 will create a suction in the passages 26 which will be manifested in the conduit 24.

Communicating with the casing 13 are a plurality of volute shaped passages 28, 29, 30, 31, the inlets of which are arranged in 25 close proximity to the periphery of and about the path of rotation of the impeller. The liquid being discharged from the peripheral pockets of the impeller will be successively delivered into the volute passages 28—29—30—31 and the movement or 30 kinetic energy of the liquid in the volute passages will operate to create a further or additional suction in the passages 26. The liquid and fluid thus delivered by the impeller will be discharged into the tank 10.

While the preferred form of the invention has been herein shown and described it is to be understood that many changes may be made in the details of construction and in 40 the combination and arrangement of the several parts within the scope of the claims without departing from the spirit of this invention.

What is claimed as new is:—

45 1. An apparatus of the character described embodying a casing provided with a volute chamber having an inlet and a discharge outlet for the liquid, a rotor within the chamber, said rotor embodying a series 50 of impellers, a second series of impellers encompassing and spaced from the first recited series, a conduit having a plurality of outlets in communication with the space between the said series of impellers, a baffle 55 arranged adjacent each of the outlets of the said conduit, the ends of each baffle terminating short of the respective proximate ends of the next adjacent baffles, and means whereby the rotor may be actuated to deliver the 60 liquid from one set of impellers to the other set and between the ends of the baffles.

2. An apparatus of the character described embodying a rotor, said rotor embodying two series of impellers, one of the 65 series encompassing the other and being

spaced therefrom, the position of the two series of impellers with relation to each other being fixed and constant, a conduit having an outlet opening communicating with the space between the impellers, means for actuating the rotor to cause one set of impellers to deliver liquid to the other set of impellers across the space therebetween, and means adjacent the said outlet opening of the conduit for interrupting the flow of liquid from 70 one set of the impellers to the other whereby the discharge of liquid from the said other set of impellers as they pass the conduit outlet will create a suction in the said conduit. 75

3. An apparatus of the character described embodying a rotor, said rotor embodying two series of impellers, one of the series encompassing the other and being spaced therefrom, the position of the two series of impellers with relation to each other being fixed and constant, a conduit having an outlet opening communicating with the space between the impellers, means for actuating the rotor to cause one set of impellers 80 to deliver the liquid to the other set of impellers across the space therebetween, and means adjacent the said outlet opening of the conduit for interrupting the flow of liquid from one set of the impellers to the other whereby the discharge of liquid from the said other set of impellers as they pass the conduit outlet will create a suction in the said conduit, the last recited means embodying a baffle projecting into the space between the two series of impellers and extending in a direction about the axis of rotation 85 of the rotor. 90

4. An apparatus of the character described embodying a rotor, said rotor embodying two series of impellers concentrically arranged, there being one or more discharge outlets leading from the conduit, the outlet of the conduit being disposed in the space between the two series of impellers and opening away from the innermost series to form a wall extending in a general direction about the axis of rotation of the rotor, to interrupt the flow of liquid from the inner to the outer series of impellers at 95 predetermined points in the rotation of the rotor, whereby the discharge of liquid from the outermost series of impellers will create a suction in the conduit at the said predetermined points. 100

5. An apparatus of the character described embodying a casing having a volute chamber therein provided with an inlet and a discharge outlet for liquid; a rotor, said rotor embodying two series of impellers, one of the series encompassing the other and being spaced therefrom, the position of the two series of impellers with relation to each other being fixed and constant, a conduit having an outlet opening communicating with the 110 115 120 125 130

- space between the impellers, means for actuating the rotor to cause one set of impellers to deliver liquid to the other set of impellers across the space therebetween, and means adjacent the said outlet opening of the conduit for interrupting the flow of liquid from one set of the impellers to the other whereby the discharge of liquid from the said other set of impellers as they pass the conduit outlet will create a suction in the said conduit. 5
6. An apparatus of the character described embodying a casing having a volute chamber, a rotor in said chamber, said rotor embodying a series of impellers, a second series 10 of impellers encompassing and spaced from the said first series to form an annular space therebetween, both of the said series of impellers rotating in unison and having a permanent fixed position with relation to each other whereby the inner series of impellers will deliver fluid to the outer series, means 15 for temporarily arresting the delivery of the liquid from the inner series of impellers to certain of the outer series of impellers, provisions whereby the flow of the liquid from the outer impellers to which the delivery of the liquid has been arrested, will create a suction, and a conduit in which the said suction will be manifested. 20
7. An apparatus of the character described embodying a casing having a chamber, a rotor in said chamber, said rotor embodying a series of impellers, a second series of impellers encompassing and spaced from the 25 said first series to form an annular space therebetween, both of the said series of impellers rotating in unison and having a permanent fixed position with relation to each other, whereby the inner series of impellers will deliver fluid to the outer series, means 30 for temporarily arresting the delivery of the liquid from the inner series of impellers to certain of the outer series of impellers, provisions whereby the flow of the liquid from the outer impellers to which the delivery of the liquid has been arrested, will create a 35 suction, and a conduit in which the said suction will be manifested. 40
8. An apparatus of the character described embodying a rotary impeller, said impeller embodying a series of impeller blades, a second series of impeller blades encompassing and spaced from the first recited series, a fluid conduit, said conduit having communication with the space between the said 45 series of impeller blades whereby the liquid delivered from the outer series of blades will create a suction in the conduit, and a volute shaped passage having its inlet adjacent the path of movement of the impeller for receiving the liquid therefrom, the movement of the liquid through the said volute shaped passage operating to create an additional suction in the said conduit. 50
9. An apparatus of the character described embodying a rotary impeller, said impeller embodying a series of impeller blades encompassing and spaced from the first recited series, said series of blades having a constant 55 position with respect to each other and being simultaneously rotatable, a fluid conduit, said conduit having communication with the space between the said series of impeller blades whereby the liquid delivered from the outer series of blades will create a suction in the 60 conduit, and a volute shaped passage having its inlet adjacent the path of movement of the impeller for receiving the liquid therefrom, the movement of the liquid through the said volute shaped passage operating to 65 create an additional suction in the said conduit. 70
- In testimony whereof I have signed my name to this specification on this 21st day of March, A. D. 1919.

BENJAMIN SKIDMORE, JR.
